UNITED STATES PATENT OFFICE.

WILLARD A. ORMSBEE, OF TAUNTON, MASSACHUSETTS.

DESIGN FOR A TIE CLIP.

Application filed November 3, 1926. Serial No. 19,581. Term of patent 3½ years.

To all whom it may concern:

Be it known that I, WILLARD A. ORMSBEE, a citizen of the United States of America, residing at Taunton, county of Bristol, State of Massachusetts, have invented a new, original, and ornamental Design for a Tie Clip, of which the following is a specification, reference being had to the accompanying drawing, forming a part thereof.

I claim:

The ornamental design for a tie clip, substantially as shown.

WILLARD A. ORMSBEE.
